Assistant Examiner — Nathaniel D Buckner

CLAIM

The ornamental design for a storage drive, as shown and described.

DESCRIPTION

FIG. 1 is a top, front and side perspective view of a first embodiment of a storage drive embodying the new design; FIG. 2 is a top view thereof; FIG. 3 is a bottom view thereof; FIG. 4 is a back view thereof; FIG. 5 is a front view thereof; FIG. 6 is a first side view thereof; and FIG. 7 is a second side view thereof; FIG. 8 is a top, front and side perspective view of a second embodiment; FIG. 9 is a top view thereof; FIG. 10 is a bottom view thereof; FIG. 11 is a back view thereof; FIG. 12 is a front view thereof; FIG. 13 is a first side view thereof; and, FIG. 14 is a second side view thereof. The broken lines shown in the figures illustrate portions of the article that form no part of the claimed design. The wavy broken lines shown in FIGS. 8-14 illustrate that the appearance of any portion of the article between the lines forms no part of the claimed design.

1 Claim, 8 Drawing Sheets
